UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPO-
RATION OF MASSACHUSETTS.

BEAM-HEAD.

1,380,669.

Specification of Letters Patent. Patented June 7, 1921.

Application filed August 23, 1919. Serial No. 319,346.

To all whom it may concern:

Be it known that I, FRANK MOSSBERG, a citizen of the United States, and resident of Attleboro, in the county of Bristol and State 5 of Massachusetts, have invented certain new and useful Improvements in Beam-Heads, of which the following is a specification.

This invention relates to heads for warp beams, reels or the like and to the method 10 of constructing the same; and has for its object to provide such a head by striking or swaging sheet metal parts into the desired shapes and connecting together these different parts, whereby this head may be produced very rapidly, of maximum strength, 15 very light in weight and at the minimum expense.

With these and other objects in view, the 20 invention consists of certain novel features of construction, as will be more fully described, and particularly pointed out in the appended claims.

In the accompanying drawings:

Figure 1— is a side elevation partly in 25 section, showing a warp beam with my improved head member attached thereto.

Fig. 2— is an enlarged front view showing a portion of the head.

Fig. 3— is an edge section on line 3—3 of 30 Fig. 2.

Fig. 4— is a front elevation showing a portion of the head and illustrating a modified form of lip for centrally locating and supporting the flange member.

Fig. 5— is a front view showing a portion 35 of a head, and illustrating another modification.

Fig. 6— is a fragmental perspective view of another modification.

Fig. 7— is a section on line 7—7 of Fig. 6.

I have herein shown and described the construction of a head member for beams, reels, spools or other similar articles of manufacture, which head is formed by folding, swaging or otherwise forming bendable or ductile metal so as to connect and lock the parts of the head together to provide an annular groove 9 about the periphery of the head to receive a band or friction member 50 to which tension may be applied by a weight, spring or other device for the purpose of preventing the beam from rotating too freely as the warp or yarn is drawn therefrom or these heads may be used for

any other purpose for which they are 55 adapted.

Referring to the drawings, 10 designates the body or barrel portion of a beam, which is preferably made in tubular form, the ends of the tube being secured to the opposite 60 heads 11 of the beam by means of bolts 14, or other suitable means. These head members are preferably constructed of a main plate 12 cut from sheet stock into disk form a plurality of ears 13 being formed 65 preferably by cutting portions from the body of the plate a short distance inward from the periphery thereof and turning these cut portions outwardly at substantially right angles to the plane of the plate, 70 which ears serve to both centrally locate and also to support the flange member 15, presently described.

This flange member 15 is preferably formed by bending a length of sheet stock, 75 see Fig. 8, into a bar 16 of substantially L-shape in cross section; then bending this L-shaped bar into circular form and fastening together its abutting ends as at 17, see Fig. 2, by welding or otherwise. This flange 80 member is then positioned over the centralizing ears 13 and its inner edge 18 is spot-welded or otherwise secured to the outer face of the disk 12 thus forming an annular trough or groove partly by the outer edge 85 of the disk and partly by the flange member secured thereto.

Instead of bending the ears 13 outwardly laterally at right angles to the plane of the disk, as illustrated in Figs. 1, 2 and 3, I may 90 form them as illustrated in Figs. 4 and 5, which is that of cutting their outer edges and setting these outer edges 20, slightly outward to serve as centralizing members for the flange member 15; or I may draw out 95 or reduce the thickness of the stock at the edge 19 of the disk 12 and fold this drawn or thinned portion back as illustrated at 19 in Figs. 6 and 7, so that this folded part will form the bottom of the groove and the L-shaped flange member will be positioned beneath this folded rim portion, but I do not wish to be restricted to any of the constructions shown as the flange member may be formed separate and secured to the disk 100 member 12 and centralized thereon and secured thereto by any suitable means.

The foregoing description is directed

solely toward the construction illustrated, but I desire it to be understood that I reserve the privilege of resorting to all the mechanical changes to which the device is susceptible, the invention being limited only by the terms of the appended claims.

I claim:

1. In an article of the character described, a head member comprising a sheet metal disk, a circular flange member substantially L-shape in cross section secured to said disk a distance within the periphery thereof to form an annular groove, said disk being provided with raised portions on its face for centrally locating and supporting said flange thereon.
2. In an article of the character described, a head member comprising a sheet metal disk, a circular flange member L-shape in

cross section and secured at one edge to the 20 face of said disk a distance within the periphery thereof and portions of said disk being bent from its normal plane to engage and centrally support said flange thereon to form an annular peripheral groove.

25

3. In an article of the character described, a head member comprising a sheet metal disk, an annular flange member L-shape in cross section and having one edge secured to said disk a short distance within the periphery thereof to form an annular circumferential groove and a plurality of integral lips raised from the plane of said disk for centrally supporting said flange member thereon.

30

35 In testimony whereof I affix my signature.

FRANK MOSSBERG.
